THIS ATTORNEY

UNITED STATES PATENT OFFICE.

GEORGE B. WEBB, OF WESTFIELD, NEW JERSEY, ASSIGNOR TO THE
WYCKOFF, SEAMANS & BENEDICT, OF ILION, NEW YORK.

TYPE-WRITING MACHINE.

SPECIFICATION forming part of Letters Patent No. 657,187, dated September 4, 1900.

Application filed June 24, 1899. Serial No. 721,685. (No model.)

To all whom it may concern:

Be it known that I, GEORGE B. WEBB, a citizen of the United States, and a resident of Westfield, in the county of Union and State of New Jersey, have invented certain new and useful Improvements in Type-Writing Machines, of which the following is a specification.

My present invention relates to that general description of card-holders for type-writing machines made the subject-matter of my Letters Patent No. 575,917, dated January 26, 1897, and has for its main object to improve the construction and to provide means whereby the card-holder may be more conveniently attached and detached from the clamping devices fixed at the end of the platen.

A further object of my invention is to so construct and arrange such means as that there shall be no projecting members to interfere with the use of the machine when writing upon cards or when used for ordinary purposes.

To these ends the invention includes features of construction and combinations of devices hereinafter described, and more particularly set forth in the appended claims.

The preferred form of the invention is illustrated in the accompanying drawings, forming part of this specification, in which—

Figure 1 is a plan view of a platen-carrier and platen, showing the invention applied thereto. Fig. 2 is a sectional view on the plane indicated in Fig. 1 by the line X-X looking in the direction of the arrow. Fig. 3 is a sectional detail view showing a spring-catch and a cam-lever in normal position on the platen. Fig. 4 is a view similar to Fig. 3, but showing the catch and lever in different positions and showing also a card-holder in end view. Fig. 5 is a perspective view of the spring-catch shown in the preceding figures. Fig. 6 is a perspective view of the cam-lever shown in Figs. 1 to 4. Fig. 7 is a perspective view of the card-holder shown in Figs. 1, 2, 45 and 4.

The same part will be referred to by the same numeral of reference.

1 indicates a platen-carrier such as is in use in the Remington No. 6 machine; 2, a roller-platen journaled in carrier 1; 3, hand-wheels on the ends of platen-shaft 4; 5, the

usual ratchet-wheel at the right-hand end of the platen 2; 6, the rear bar of carrier 1; 7, ears or lugs attached to or formed on bar 6; 8, arms pivotally connected at 9 to ears 7; 10, pressure-rolls journaled in ears of arms 8; 11, springs attached at 12 to arms 8 and bearing against lugs 13 on bar 6 to press rolls 10 against platen 2; 14, a rock-shaft journaled in frame 1; 15, arms pivoted on shaft 14 and carrying the platen scale-bar 16, against which the lower ends of springs 11 bear, as shown; 17, arms on shaft 14, which bear on plates 18, secured to arms 8, and press the arms 8 and rollers 10 away from the platen when moved rearward by the rocking of the shaft 14; 19, a pressure-roll in front of the platen; 20, a pivoted arm carrying roll 19; 21 22, clamp members pressed against the front bar 23 of carrier 1 by spring 24; 25, a screw passing freely through member 22 and engaging a threaded hole in member 21 and provided with a knurled head 26, the clamp carrying the arm 20 and being adjustable along bar 23.

The above-described devices are usually to be found in the aforesaid Remington No. 6 type-writing machine and are not all fully shown herein.

In this construction the platen comprises a wooden core 27 and a rubber sheath or cover 27^a, the core extending out beyond the sheath at each end of the platen. Segmental plates 28 and bosses 29 thereon are let into the core 27 where exposed, as aforesaid, and are secured to the core, as by wood-screws 30, in order to provide durable parts for coaction with devices to be described. A segmental groove or depression is formed in the core to receive the segmental metal plate 28, and a radial hole is bored through the core to receive the boss 29 on the under side of said plate. The bosses or hubs 29 are hollow and are internally screw-threaded to receive screws 31, by means of which plate-springs 32 are adjustably secured to the platen ends. The springs 32 are curved to have about the same radius as the reduced end portions of the platen and are provided with longitudinal slots 33, through which the screws 31 pass. The ends 34 of the springs 32 which are adjacent the slots 33 are curved outwardly, as shown in Fig. 2; and the free ends 35 of the springs 32

are bent inwardly, as shown clearly in Figs. 2, 3, 4, and 5. Adjacent the ends 35 each spring is formed with a U-shaped slot 36, leaving a spring-tongue 37. The side bars 38 of the slots 36 are curved or bent outwardly to form bearings 39 for a purpose presently to be explained. For the purpose of conveniently forcing or lifting the ends 35 of the springs 32 away from the platen, the 10 springs themselves extending circumferentially thereof, I provide levers 40 with ears or lugs 41, arranged at a distance apart such that they may straddle the tongues 37 aforesaid with ease. The inner faces 42 of ears 15 41 are curved to the same radius as the outer faces of plates 28, for a purpose soon to be explained. The lugs 41 of levers 40 are perforated transversely for the reception of pins 43, which are forced in to be rigid each with 20 its lever 40 and which between lugs 41, at least, are flattened on the side next faces 42 to coact with the spring-tongues 37 aforesaid to hold levers 40 down in the position shown in Fig. 2, the projecting ends of pins 25 43 being journaled in bearings 39 aforesaid. The bearings 39 are at one side of pins 43 and the tongues 37 at the opposite side thereof, thus retaining the levers 40 in place. The levers 40 are curved to lie below the periphery of the rubber sheath, and the ends of lugs 30 41 are rounded, as shown, so as to slide or work easily on the plates 28 whenever the levers are turned to and from the position shown in Fig. 4. In turning from the position 35 thereof shown in Fig. 3 to the position thereof shown in Fig. 4 the lever 40 lifts the spring 32 from the position thereof shown in Fig. 3 to the position thereof shown in Fig. 4. The extreme end 44 of lever 40 is turned outwardly in order that the lever may be grasped more easily by the finger. When the lever 40 is down in the position shown in Fig. 3, the faces 42 aforesaid form stops for coaction with plate 28 in limiting the motion of 45 the catch 35 inwardly.

The card-holder 45 comprises a plate curved or concaved to conform to the curvature of the platen and having its card-holding edge or lip 46 parallel with the axis 4 of the platen 50 when in place thereon, as hereinafter set forth. The main portion of plate 45 is shown as of the same length as the rubber sheath aforesaid, with a sunken part 47 at the right-hand end of the platen, the lip 46 ending as 55 it reaches such part 47. Part of plate 45 when on the platen extends over the reduced ends thereof, as at 48, and the extensions 48 are formed with or have attached thereto blocks 49, which are formed with notches 50 60 for coaction with catches 35 aforesaid. By preference the notches 50 are formed by faces radial to the platen when the plate 45 is thereon and by opposing faces 51, which are oblique or inclined inwardly (relative to the 65 platen) toward said radial faces 51^a, and the projections 52 of blocks 49, on which said inclined faces are located, are formed with

wedge-shaped edges. The projections 52 are at the side of blocks 49 opposite to or away from the card-holding lip 46.

The operation of the foregoing devices is as follows: Suppose the parts to be in the positions shown in Fig. 3 and it be desired to put the card-holder on the platen and to insert a card. Each lever 40 is lifted by the 70 finger to the position shown in Fig. 4, thus lifting each spring-catch 35, as shown in Fig. 4. In this position the cam-lever 40 locks the catch in its elevated position. The plate 45 is next placed on the platen with its 75 notched blocks 49 under the catches 35, the levers 40 are turned back toward the platen and are snapped down by the springs 32, and the catches 35 engage the notches 50. The catches 35 may strike the inclines 51 80 85 and cam or force the holder 45 slightly circumferentially of the platen until the radial faces 51^a of blocks 49 aforesaid stop or arrest such motion by coming in contact with the ends of catches 35, as shown in Fig. 2, in 90 which position of the parts the shoulder at the line of joinder of lip 46 to plate 45 is parallel with the axis of the platen, and so with any line of print thereafter made while the card-holder is thus locked securely on the 95 platen. The platen may be turned backward and forward at will while the holder is in place, except that the holder cannot pass scale-bar 16 as the platen is rotated backward.

In the use or operation of the contrivance the leading edge of a card 53 is inserted under the ledge 46 and into the space or pocket formed between the said ledge and the platen, and the platen is then rotated to 105 bring the card to the impression-point. The machine shown belongs to the so-called "under-strike" class, and in such a machine the platen, card-holder, and the card are rotated down to bring the card to the under 110 side of the platen for printing. At Fig. 2 the card is in position for printing, at which time it will be observed that the leading edge of the card is held by the lip or ledge 46, the bar 16, and the roller 10, so that the 115 card is bent to conform accurately to the surface of the platen, and that in feeding the card by rotating the platen the rollers 10 act to bend the card about the platen. Of course a feed-clamp, pressure-blade, deflector, or 120 other known substitute for the feed-roller may be used instead of or in conjunction with the latter.

The card-holder may be adjusted circumferentially of the platen, and so with respect 125 to the ratchet-wheel 5, by means of the screws 31, the slots 33, and springs 32, and thus vary the distance from the top of the card at which the writing may begin, since the teeth of the ratchet-wheel 5 determine the longitudinal 130 planes of the platen on which the type strike to give impressions. In other words, the leading edge of the card may be stopped at different distances from the plane in which

the type strike by moving or adjusting the plate 45 circumferentially through the medium of the slotted springs 32 and screws 31. When a card has been brought to the desired 5 position, the types are actuated in the usual way to effect the printing.

From the foregoing it will be observed that the spring-catch at each reduced end of the platen when in normal condition lies substantially concentric with the platen and that the handle end of its lifting or operating lever is so shaped and connected thereto as that when the lever is likewise in normal condition it is substantially concentric with 10 said spring-catch and lies down close upon the same and below the plane of the working face of the platen both when the card-holder is in place and when it is removed from the machine, thus providing a neat, 15 compact, and effective construction and one in which none of the parts or members thereof project or protrude to an extent such as to interfere with the work. It will also be observed that the lever is pivoted between its 20 ends upon the spring-catch itself and that the inner or cam end of the lever is adapted to bear on the platen or upon the plate 28 thereon in the operation of lifting or raising the spring-catch and also that when both 25 30 spring-catches have thus been lifted and are being held up by their respective levers, as shown at Fig 4, the card-holder may be readily placed in position upon the platen for engagement with said spring-catches, and 35 while there held with one hand the levers may be pushed down with the other hand to release the catches and enable them to engage with the notched portions of the card-holder. When the work with the card-holder 40 is finished, the latter may be conveniently detached from the platen by simply raising the levers and their connected spring-catches, which is an operation requiring only a few seconds. In fact, the card-holder may be attached and detached in much less time, with 45 greater facility, and with less muscular effort than the card-holder shown in my aforementioned prior patent, it being necessary in the last-mentioned construction to force or wedge 50 the card-holder into and out of position against the tension of quite stiff springs and which are operations that cannot be performed with ease and expedition.

Of course the invention is equally applicable to the so-called "front-strike," "top-strike," or "visible-writing" machines.

What I claim as new, and desire to secure by Letters Patent, is—

1. The combination of a platen, spring-catches secured thereto, a card-holder provided with notched ends or arms, and levers connected to said spring-catches for opening and closing the same.

2. The combination of a platen, movable spring-catches secured thereto, a card-holder provided with notched ends or arms and cam-levers for operating said catches.

3. The combination of a platen, movable plate-springs each secured at one end to the platen and having its free end turned inwardly to form a catch, and a card-holder having blocks with adjacent inclined and stop faces whereby the inturned ends of the said springs coact with said stop and inclined faces to force the holder to and to retain it in position on the platen. 70 75

4. The combination of a platen, movable plate-springs each secured at one end to the platen and having its free end turned inwardly to form a catch, a card-holder having ends provided with radial stop-faces and outer faces inclining inwardly to said stop-faces and forming notches whereby the in-turned ends of said springs and said radial and inclined faces coact to force the holder 80 into and to retain the same in position, and cam-levers connected to and operating said springs to lift said ends out of engagement with said notched ends of the holder. 85

5. The combination of a platen, spring-catches secured to the ends thereof, cam-levers for moving the free ends of said catches away from said platen, and a card-holder provided with projecting cam-blocks adapted to coact with said catches in locking the holder 90 95 to the platen.

6. The combination of a platen, plate-springs adjustably secured to the ends thereof and having inturned catches at their own free ends and also having each a slot near the said 100 catches, and the side bars at said slots being formed with bearings, cam-levers having fulcrum or pivot pins adapted to said bearings, and a card-holder having notched blocks connected thereto and adapted to coact with said 105 catches in locking the holder to the platen.

7. The combination of a platen having reduced ends, segmental plates having inwardly-projecting bosses or hubs, both plates and hubs being let into said ends, means for attaching said plates to said ends, slotted plate-springs, screws passing through said slots and adjustably securing the springs to said plates and hubs, and said springs also having U-shaped slots with transverse bearings in the outer bars thereof, cam-levers, pins thereon adapted to rest and to be held by the tongues of the U-slots in said bearings, catches at the free ends of said slotted plates, a card-holder, and notched blocks connected 115 120 with said holder and adapted to coact with said catches to retain the holder in place on the platen.

8. The combination of a platen having reduced ends, plate-springs secured each near 125 or at one end to said reduced ends and provided each with a U-shaped slot near its free end so as to produce a spring-tongue, bearings in the side bars of the U-slots, cam-levers adapted to coact with said reduced ends 130 to lift said springs and journaled in said bearings and having flattened parts coacting with the spring-tongues of the U-slots, and a card-holder having ends adapted to coact with the

ends of said springs in detachably securing the holder on the platen.

9. The combination of a platen having reduced ends, plate-springs secured each at one end to said reduced platen ends and having their free ends turned inwardly and provided with **U**-shaped slots near said free ends, bearings in the side bars of said slot, cam-levers provided with parallel lugs or ears having inner faces concentric with said reduced ends and adapted to straddle the tongues of said slots, pins passing through and projecting beyond said lugs and journaled in said bearings and having each a flattened side between said lugs for coaction with said spring-tongue, and a card-holder having notched ends for coaction with the said inturned spring ends.

10. The combination of a platen having reduced ends, plate-springs secured each at one end to said reduced platen ends and having their free ends turned inwardly and provided with **U**-shaped slots near said free ends, bearings in the side bars of said slots, cam-levers provided with parallel lugs or ears having inner faces concentric with said reduced ends and adapted to straddle the tongues of said slots, pins passing through and projecting beyond said lugs and journaled in said bearings and having each a flattened side between said lugs for coaction with said spring-tongue, and a card-holder having ends provided with ra-

dial stop-faces and blocks connected to said ends and having outer faces inclining inwardly to said stop-faces, whereby said in-turned spring ends and said inclined faces 35 coact to force the holder into and to retain it in position when the cam-levers are released or turned inward.

11. The combination of a platen, spring-catches secured thereto, a card-holder provided with notched ends or arms, and levers pivoted between their ends on said spring-catches and adapted to bear at their inner ends on the ends of the platen.

12. The combination of a platen, spring-catches secured thereto, a card-holder provided at its ends with means to engage said spring-catches, and levers connected to said spring-catches and adapted to lift the same by bearing upon the platen and having their 50 handle portions arranged exteriorly of said spring-catches and so shaped or formed as substantially to match and lie close to the same when in normal position.

Signed in the borough of Manhattan, in the city of New York, in the county of New York and State of New York, this 23d day of June, A. D. 1899.
